UNITED STATES PATENT OFFICE.

CHARLES H. ALLEN, OF ATTLEBORO, MASSACHUSETTS.

ARTICLES OF JEWELRY ARRANGED FOR HOLDING INTERCHANGEABLE GEMS OR STONES.

937,502.

Specification of Letters Patent.

Patented Oct. 19, 1909.

Application filed March 2, 1909. Serial No. 480,874.

To all whom it may concern:

Be it known that I, CHARLES H. ALLEN, a citizen of the United States, residing at Attleboro, in the county of Bristol and State 5 of Massachusetts, have invented certain new and useful Improvements in Articles of Jewelry Arranged for Holding Interchangeable Gems or Stones, of which the following is a specification.

10 This invention relates to a new and novel improvement in gem-settings for articles of jewelry, such for example, as scarf-pins, brooches, buttons, finger-rings, and kindred articles, and it consists in the peculiar construction, arrangement and combination of parts, all as hereinafter set forth and claimed.

15 The object sought to be attained by the present invention is to provide articles of jewelry, say of the class above referred to, with simple and inexpensive permanent or integral settings adapted to be readily manipulated for the mounting and securing therein of interchangeable stones, gems or other ornaments. It may be stated here that 20 prior to this invention articles of jewelry have been devised in which interchangeable gem-settings are employed; in such former constructions, however, each mounting, which includes the setting and its stone permanently secured therein and constituting a 25 unitary member, is bodily removable. In some cases practically the entire front, carrying the setting and stone, is removably secured to the back or base of the article, thereby providing a degree of interchangeability.

30 In the present case the article of jewelry embodying the improvement forming the subject of this application for patent is provided with a permanent or non-detachable setting having normally arranged means for positioning the individual gem or ornament in the setting, and manually controlled self-locking means for securing and maintaining 35 the gem in place therein; the construction being such that individual stones or ornaments varying in species, quality, color, form, &c., may be quickly interchangeably substituted and detachably secured in the setting 40 and its seat as desired; it being understood that the base portions proper of the stones are all substantially alike in form and size, corresponding with the seat of the setting in which they are to be mounted.

45 In the accompanying sheet of drawings,

Figure 1 represents in enlarged scale a front elevation of a scarf-pin or "stick-pin" embodying the invention. Fig. 2 is a corresponding side view. Fig. 3 is a view showing the obverse face of the front or base member itself, the stone, &c., being omitted. Fig. 4 is a corresponding view showing the reverse side of it. Fig. 5 represents the obverse face of the back member, detached. Fig. 6 is a longitudinal sectional view, enlarged, taken substantially on line 6-6 of Fig. 1. Fig. 7 is a perspective view showing one form of a stone or ornament detached from the setting. Fig. 8 is a similar view of the same, showing a slight modification. Fig. 9 represents, enlarged, a front elevation of a cuff or collar-button embodying the improvement. Fig. 10 is a corresponding back view, and Fig. 11 is a vertical sectional view, taken substantially on line x-x of Fig. 9.

50 The following is a detailed description of the invention: The article of jewelry, as for example, a scarf-pin A embodying the improvement and shown in Figs. 1 to 8, consists of a head comprising the front member 55 a, the back d, and a removable stone or ornament B. A bent wire stem or pin proper t is constructed so that its upper end part passes through said back d and is soldered to the inner face of the front member 60 a at a point near the top, as clearly shown in Fig. 6. The member a is formed or struck-up from suitable thin sheet-metal stock. As represented the general shape of the member 65 is oval, its central portion being slightly depressed or recessed to form a flat seat f for the stone or ornament B. At predetermined places around the edge of the recessed part the metal is cut and the corresponding portions of the stock bent outward at an inclined 70 angle to the seat so as to produce a plurality of positively positioned V-shaped integral prongs or fingers b whose free ends extend inward over the marginal edge of said seat, as clearly shown. A clear opening c is 75 formed say through the lower portion of the member a adapted to freely receive the movable prong d¹ of the back member d, soon to be described. The rear face of member a has also a circumscribing shallow outer rim or flange a¹, the lower end of which is cut away to produce a narrow recess d². See Fig. 4. The said member d is also formed 80 from suitable thin sheet-metal having a degree of resiliency, as German silver; its outer 85

periphery is made to conform to the inner contour of the flange a^1 and is soldered to the upper portion of the latter. The member constitutes a flat back for the head portion of the article A and has a hole t^1 (Fig. 5) therein at one end through which the pin-shank t extends. The opposite or lower end of member d has an integral tongue fitting said recess d^4 and terminates therebeyond in a suitably shaped lug or finger-piece d^3 . The plate is further provided with an integral prong d^1 produced by bending the stock within the opening d^2 . The free end of the prong extends upward through the front member's opening c and when in use is adapted to engage the corresponding part of the ornament.

The form or shape of the insertible stone or ornament B may be made as desired and produced from precious, semi-precious or artificial stones or other substances. The back portion of the member B is adapted to fit the seat f , the said prongs being employed for holding the stone in position thereon. If desired the bottom of the stone and its lower edges may be provided with a fixed metal shoe or lining h ; this latter serves not only to protect and conceal the marginal edges of the member B but at the same time may be quite ornamental.

Assuming now that the front and back members, a and d , have been constructed, arranged and connected together substantially as described, the manner of mounting a stone, as B, therein and removing it therefrom is as follows: The stone selected is first positioned with respect to the seat and then pressed in an endwise or longitudinal direction past the prong d^1 of the yielding plate d (see dotted lines Fig. 6) and between the fixed side prongs until arrested by the stationary upper end prong b , at which instant the plate d with its prong d^1 springs or snaps back to the normal position, thereby positively locking the stone in place, substantially as represented in Figs. 1, 2 and 6. The stone may be quickly and readily removed from its setting so as to insert another therein by first simply pressing rearwardly upon the extension d^3 of the plate d , say to the dotted position shown in Fig. 6, followed by the substitution of the selected stone as before described and removing the pressure from the plate, the latter by reason of its resiliency acting to automatically project its prong d^1 through the seat opening c and engage the adjacent end of the stone, thus locking it in position. The finger pressure may be removed from the plate d immediately after the first named stone has been released, followed by inserting the new stone as first described.

This invention is equally adapted to be employed in other articles of jewelry, as for example, in a collar or cuff-button A, as

represented in Figs. 9, 10 and 11, in which the general construction and arrangement of parts as well as the manner of operation are substantially the same as hereinbefore described. In the last-named figures, however, the shank s is disposed centrally of the front member a and is soldered to its reverse side, the outer or free end of the shank is provided with a shoe or back head u in a well-known way.

By means of the invention it will be apparent that a single article of jewelry provided with the improved safety setting may be readily manipulated to remove therefrom and to receive therein interchangeable stones or ornaments at the pleasure of the wearer.

The cost of producing the improved device is comparatively small; it may be made very attractive and ornamental; it is simple in construction and is arranged so as to hold the gems or stones therein in a safe and efficient manner. As thus devised a single article, as a scarf-pin, cuff-button, finger-ring, &c., as the case may be, and provided say with a number of independently interchangeable gems varying in color, character or species, is obtained at a greatly reduced cost while at the same time possessing substantially all the advantages and may be substituted for a corresponding number of units, each carrying a fixed or non-removable single gem.

Having thus described my invention what I claim as new and desire to secure by United States Letters Patent is:—

1. In articles of jewelry of the character described, the combination with the front member provided with bent prongs integral therewith, of a resilient back member having a locking prong or lug normally extending through the wall of the front member and constituting with the other prongs a setting adapted for removably securing a gem or stone therein.

2. In articles of jewelry of the character described, the combination with the front member thereof having a recessed seat and normally bent prongs disposed with relation thereto so as to form a setting, of a resilient back plate element secured to the front member provided with a lug or prong normally projecting forwardly through the latter arranged to coöperate with said other prongs for temporarily positioning and removably locking a gem or stone in the setting.

3. In articles of jewelry of the character described, the combination with the relatively stationary front member provided with a base or seat having integral suitably disposed bent prongs struck-up therefrom to form a partial setting, of a resilient complementary locking prong member of the setting extending through said base, and means connected with the locking-prong

adapted to be manipulated to permit of the insertion and removal of interchangeable stones.

4. In articles of jewelry of the character described, the combination with the front member having setting prongs struck-up therefrom and provided at the rear with a narrow circumscribing rim or flange having a recess therein, of a depressible resilient back plate seated in said flanged and recessed part and secured at one end thereof, and a bent prong or lug integral with said plate having its upper or free end portion normally extending through the front member for temporarily locking in position a stone or ornament inserted in the setting.

5. In articles of jewelry of the character described, a head portion consisting of a front member having a plurality of fixed 20 permanently bent and positioned outer prongs arranged to form a setting, a resilient back member secured to the front member having a locking-prong integral therewith disposed with relation to the other 25 prongs, and a projection or lug connected with the back member adapted to be readily manipulated for depressing the back and its prong so as to release a stone temporarily mounted in the setting.

30 6. In articles of jewelry of the character

described, the combination of a front member provided with fixed permanently positioned outer setting prongs, a self-positioning resilient back plate member having one end thereof fixed to the rear side of the 35 front piece provided with a locking-prong arranged to coöperate with the other prongs for temporarily securing a stone in the setting, and a shank or stem member having one end thereof passing freely through said 40 back plate and being rigidly attached to the front member.

7. In an article of jewelry of the character described, the combination of a front member provided with a plurality of outer fixed 45 positioning prongs arranged to form a setting, a thin resilient back plate yieldingly secured to the front member having an integral locking-prong movable with the plate and normally coöoperating with the said 50 other prongs, and a base-protected stone removably seated in the setting and maintained in position by the said fixed and movable prongs.

In testimony whereof I have affixed my 55 signature, in presence of two witnesses.

CHARLES H. ALLEN.
